OIL GAS GENERATOR

Walter B. Harris, Bayside, Long Island City, N. Y.

Application March 12, 1934, Serial No. 715,082

8 Claims. (Cl. 48—94)

This invention relates to an oil gas generator for generating oil gas from hydrocarbon oils by causing same to react with superheated steam under heat influence.

5 This invention is an improvement on the oil gas generator shown and described in Patent No. 1,903,042, issued on March 28, 1933, to Leonard B. Harris.

The mixture of the oil and superheated steam 10 is introduced into a high temperature zone produced by an incased electric heating element, the said heating element being fixedly mounted within in a gasifying chamber in an oil gas making generator.

15 Heat from the heating element is used to produce saturated steam in a boiler positioned in the generator. A coil leading from the boiler is used to produce superheated steam. The oil and superheated steam are introduced into a heated 20 gasifying chamber as a mixed spray by means of an injector nozzle; the nozzle is so constructed that the mixed spray issuing therefrom will spread in cylindrical form throughout a cylindrical space forming the gasifying chamber; the 25 said oil spraying taking place only when the heating element is in an incandescent state and the said gasifying chamber is thereby heated to a reaction temperature.

Water is delivered in a regulated quantity to 30 the boiler, thus determining the quantity of steam issuing from the nozzle. The energy of the superheated steam passing through the nozzle at a high velocity is used to inject a regulated quantity of oil, the mixture of oil and 35 steam being caused to enter simultaneously into the gasifying chamber.

An object of this invention is to provide regulating means for supplying relatively proportioned quantities of hydrocarbon spray and superheated steam.

40 Another object of this invention is to cause the energy of a superheated steam jet to lift a regulated quantity of hydrocarbon oil from a level below an injector nozzle into a gasifying 45 chamber within an oil gas generator.

Another object of this invention is to cause a mixed spray of oil and superheated steam to be introduced into a heated gasifying chamber and cause the steam to dissociate into hydrogen and 50 oxygen and reaction between hydrogen and carbon.

With the above and other objects in view the invention will be hereinafter more particularly described, and the combination and arrangement of parts will be shown in the accompany-

ing drawings and pointed out in the claims which form part of this specification.

Reference will now be had to the drawings, wherein like numerals of reference designate corresponding parts throughout the several 5 views in which:

Figure 1 is a side view in elevation of the oil gas making unit, showing the oil gas generator, water seals, scrubber and bellows; the water seals and scrubber being in section.

10 Figure 2 is a longitudinal sectional view of the oil gas generator.

Figure 3 is a fragmentary portion of the upper end of the oil gas generator and shows two electric plug terminals.

15 Fig. 4 is an enlarged view of the injector body.

In the drawings, reference character 10 indicates an oil gas generator comprising a gas-tight metal container 11, preferably of cylindrical shape and having covers 12 and 13. The lower cover 13 is provided with a pipe 16 which is connected to a trap and water seal member 17 and to a scrubber or washer 18. A gas conduit 19 leads from the scrubber 18 to a flexible gas bag or bellows 20; the functioning of this flexible gas bag being to expand and contract 25 and operate a pressure switch which controls the electric current and water supply to the oil gas generator, as described under operation. The entire apparatus is mounted on a foundation plate 21.

30 In the central portion of the container 11, best shown in Figure 2, is an annular boiler 22 for generating saturated steam, and a coil 14 serving to superheat the steam generated in the 35 boiler. The superheating coil 14 is connected to the upper end of the boiler. The boiler 22 comprises an inner wall 23 and an outer wall 24 forming a water and steam space 25 between them. The boiler 22 may be supplied with water from any suitable pressure water supply, the 40 quantity of water being regulated by a valve 26.

45 Fixedly mounted in the oil gas generator 10, best shown in Figure 2, is an insulation member 27, which is screwed into a threaded aperture in the upper cover 12. The insulation member 27 is provided with apertures for bolts 28, serving to support an electrical conducting retaining ring 29. One of the bolts 28 serves as a terminal to which an electric lead wire 30 is connected. The wire 30 is connected to a push plug terminal or contact pin 31. A wire 32 from a plug terminal 33, shown in Figure 3, is connected to a spring-pressed member 34 which exerts pressure on one end of an electrode or heat-

ing element 35. The said spring-pressed heating element 35 contacts at its other end with an electrical conducting housing 36. The housing 36 forms a shield or casing for the electrode 35 and serves to prevent contact between the oil and the electrode.

Electric current from the plug terminal 33 may thus flow through the wire 32 through the spring-pressed member 34, thence through the 10 electrode 35, returning through the housing 36, through retaining ring 29, through one of the terminal bolts 28, through lead wire 30 to the plug terminal 31, and furnishes a continuous 15 supply of electric current to the electrode or heating element 35. The heating element 35 and the housing 36 are suspended from the retaining ring 29. The heating element and housing are of a length to be substantially co-extensive with the length of the generator 10 and 20 terminate a short distance above the cover plate 13, so that the injector 93 in the cover plate 13 can be placed in longitudinal alignment with the said heating element and housing. Thus the 25 conical mixed spray 92, from the injector 93 on its passage through the chamber 37, completely surrounds for its entire length the housing 36 of the heating element 35 in the gasifying chamber 37. An insulation bushing 86 centralizes the electrode 35 in the housing 36. Surrounding the 30 electrode housing 36 is a conical tubular member 38 resting on the cover plate 13 and extending above the superheating coil 14. The tubular member 38 has perforations 39 at its upper end and is insulated from the electrode housing 36 35 by means of a non-conducting bushing 40. The cylindrical chamber 37 between the housing 36 and the tubular member 38 serves as a reaction zone in which oil gas is generated.

The upper coil 42 of the coil 14 is extended 40 downward in a generally vertical direction in the cylindrical space between the tubular member 38 and the inner wall 23 of the boiler 22. The tubular member 38 is recessed longitudinally inwardly on one side to bring the extension 43 45 of the coil 42 as close as possible to the heating element 35 so as to impart the greatest amount of heat to the steam in its passage through the said extension 43. The pipe 43 passes through the lower cover 13 and connects by means of an 50 elbow valve 44 to an injector body 45.

The injector body 45 is provided with an upper extension 46 which passes through an aperture in the cover plate 13 and extends into the gasifying chamber 37. The upper extension 55 46 is provided with a cylindrical recess 47 adapted to receive a knife-edged cup-shaped injector nozzle 48. At the bottom of the recess 47 is formed an annular groove 49 which communicates through a passage 50 with the valve 44, 60 thus supplying superheated steam from the coil 14 to the nozzle 48. A circumferential knife-edge 51 is formed at the upper portion of the nozzle 48. A tapering annular space 52 is provided between the cup-shaped nozzle 48 and the circular wall of the recess 47. An annular plate 65 53 has been mounted at the upper surface of the extension 46 and forms with the nozzle 48 an annular ribbon-like orifice or oil passage 54. A circumferential groove 55 has been formed in the upper face of the extension 46 and communicates with a generally vertically positioned passage 56 provided in the injector body 45 and connects at its lower end with an oil supply pipe 70 57.

75 The steam will pass through the superheating

coil 14 in a regulated quantity and pressure and pass through the annular space 52 around the injector nozzle 48 at a high velocity.

The oil supply for the injector nozzle is stored in a container 58 positioned below the level of 5 the nozzle. A regulating sight-feed needle-valve 60 is attached to the oil container 58. A sole- 10 noid controlled oil valve 61 is placed in the oil pipe line 57, which connects the oil container 58 and the injector 93.

The energy of the superheated steam jet passing through the nozzle 48 at high velocity is sufficient to lift the oil from the lower level 84 in the oil container 58 to a higher level at the 15 point of exit 85 of the nozzle 48. The superheated steam mixes with the oil and forms a mixed spray of oil and superheated steam. The mixed spray is introduced into the gasifying chamber 37 around the electrode 35.

As shown in Figure 1, a water seal member 62 20 is secured to the top of the foundation plate 21 and has a passage 63 through which the gas passes into a water seal bend 64 contained therein. An overflow connection 65 has been provided on one side of the water seal member 25 62 to allow overflowing into a U-shaped pipe 66. A perforated plate 67 has been provided in the scrubber 18 to act as a support for the scrubber medium 68. The flange 69 of the scrubber 18 is bolted to the flange 70 of the water seal member 30 62. The scrubber 18 is provided at its upper end with a cover plate 71 to which is connected the gas conduit 19. An inlet pipe 72 admits water to a spray ring 73 which sprays on a perforated plate 74 so that water is distributed over the 35 entire cross-section of the scrubber.

The bellows 20 comprises a hollow casing 75 for a flexible bag (not shown) and having an inlet 76 and an outlet 77. At the center of the bag where the expansion and contraction of the 40 gas bag is most effective there has been provided a movable rod 78 which may be suitably connected at its free end to a pressure switch 79. The switch 79 controls the supply of electric 45 current for starting and stopping the gas making unit as a whole. The operator sets the pressure at which the bellows will operate the pressure switch 79.

It is to be noted that the spring 81 is positioned intermediate an insulating bushing 88 50 and a thrust collar 89. A threaded nut 90 serves for adjusting the pressure on the spring. The pressure exerted by the spring 81 against the thrust collar 89 is imparted through the spindle 34 directly against the upper end of the electrode 35 and causes the electrode to be resiliently forced into electrical contact against the lower end of the conducting housing 36. The internal diameter of the housing 36 is larger than the outside diameter of the electrode 35. The housing 36 encloses the electrode and prevents contact between the spray and the electrode.

The operation of the oil gas generator as a whole is as follows:

The water supply valve 26 is regulated to deliver a measured quantity of water through a sight feed device 80 into the boiler 22. The regulating oil valve 60 is set to supply a measured quantity of oil.

The bellows 20 when empty will collapse, 70 thereby operating the pressure switch 79 and cause a continuous supply of electric current to flow through the lead 30, through the heating element 35 and the electrical conducting housing 36, bringing the electrode and the housing 75

to a predetermined temperature, thereby heating the gasifying chamber 37. The pressure switch 79 will also open the electrically controlled water valve 83 supplying water to the 5 boiler 22, forming saturated steam. The steam passes through the heating coil 14 where it is superheated. The superheated steam from the coil 14 is delivered into the gasifying chamber 37, through the injector 93 which is of the constantly open nozzle type. When a predetermined temperature has been reached in the gasifying chamber 37, the heating of the thermocouple 81 inside the chamber 37 will cause a thermoswitch 82 to close an electric circuit. Said 10 circuit will open up the solenoid controlled oil valve 61 and cause the superheated steam flowing through the nozzle 48 to lift the oil from the low level 84 in the float controlled oil container 58 to the higher level at the point of exit 85 in 15 the nozzle 48, where the oil mixes with the steam and forms a mixed spray of oil and superheated steam. The mixed spray 92 is projected in cone-shaped form into the gasifying chamber 37 around the electrical conducting housing 36. 20 The quantity of oil delivered into the oil gas generator 10 through the nozzle 48 being regulated by the needle valve 60 in proportion to the measured quantity of water being delivered. As 25 the mixed oil and steam spray passes through the gasifying chamber 37 when the electrode is in an incandescent state the steam will react with the hydrocarbon and form oil gas.

The gases generated in the gasifying chamber 37 will pass upwardly in the tubular spray confining member 38, through the perforations 39, thence downward around the outside of the spray confining member 38, around the coil 14, and through the annular space formed by the inner wall 23 of the boiler and the tubular member 38 and will leave the generator through the pipe 16.

The hot gases in passing over the external surfaces of the coil 14 will further cause the steam in the coil to become superheated. The 45 gas will pass through the gas passage 63 of the water seal member 62, shown in Figure 1, and thence through the seal pipe 64, extending below the water level indicated by W. L. The oil 50 gas will then rise through the scrubber 18 meeting the wash water spray descending through the scrubber medium 68 from the perforated plate 74, and will then pass out through the gas conduit 19 to the bellows 20. The bellows 20 will become expanded as it fills with gas and at 55 the predetermined pressure will operate the pressure switch 79 and cut off the electric current to the heating element 35 and to the electrically controlled water valve 83. The thermocouple 81 in cooling will operate the thermoswitch 82 which will shut off the oil valve 61, thereby stopping gas making. When the pressure drops to a predetermined point, the bellows contracts, operating the switch 79 and causing the electric current to flow and the gas making 60 to automatically start again. The bellows 20 from its outlet 77 can be connected to a gas storage tank (not shown) and which on reaching the predetermined pressures will cause the bellows 20 to function in unison to start and 65 stop the gas plant. It will be understood however, that when the gas bag collapses and throws in the pressure switch 79, sending current into the heating element 35, the gas making will not commence until the heat in the gasifying chamber 37 has reached the predetermined tempera-

ture at which the thermoswitch 82 is set. In other words, the pressure switch 79 can cut off the electric current supply, but cannot start the gas making without the cooperation of the thermoswitch 82. The pressure switch 79 is arranged in circuit with a source of current supply through the cable 91.

It is to be noted that the water seal in the trap 17 and the water seal in the member 62 serve to seal the gas generating chamber 37 against any air leaking into said chamber. The water seals prevent an explosion. It is obvious that the said seals do not prevent the passage of the generated gases from the generating chamber to the scrubber.

I claim:

1. In an oil gas generating apparatus, a sealed oil gas generating chamber, a one-piece encased and shielded electrically heated heating element depending from one end of said chamber, 20 and means spaced away from the lower end of said heating element and positioned at the opposite end of said chamber for injecting a continuous annularly formed mixed spray of steam and oil around the outside of the shielding casing 25 of said heating element when said element is at a temperature at which steam reacts with hydrocarbon, said shielding casing serving to keep said heating element wholly out of contact with the gases generated by said reaction. 30

2. In apparatus for generating oil gas, a sealed oil gas generating chamber, a one-piece encased and shielded elongated electrically heated heating element fixedly hung from one end of said chamber, means spaced away from the lower end of 35 said heating element and positioned at the opposite end of said chamber for causing an annularly formed steam and oil spray to be injected continuously into said chamber around the outside of the shielding casing of said heating element when said element is at a temperature 40 at which steam reacts with hydrocarbon, said injecting means comprising an annular nozzle having a ribbon-like orifice, the axis of said nozzle being in longitudinal alignment with said heating element, said casing serving to wholly shield said heating element from the gases generated by said reaction.

3. In apparatus for generating oil gas, a sealed oil gas generating chamber, a one-piece encased and shielded elongated electrically heated heating element provided with a continuous supply 50 of electric current and being fixedly hung from one end of said chamber, means spaced away from the lower end of said heating element and 55 positioned at the opposite end of said chamber for causing an annularly formed steam and oil spray to be injected into said chamber around the outside of the shielding casing of said heating element, said injecting means comprising a nozzle having an annular ribbon-like orifice and said nozzle being constantly open, said casing serving to wholly shield said heating element from the gases in said generator. 60

4. In apparatus for generating oil gas, a sealed oil gas generating chamber, a one-piece encased and shielded electrically heated heating element provided with a continuous supply of electric current and being fixedly hung from one end of 65 said chamber, means for delivering a regulated quantity of steam into a superheating coil and into an injecting nozzle in longitudinal alignment with said heating element in said chamber, and means spaced away from the lower end of said heating element and causing a regulated quantity of 70 75

mixed steam and oil spray of annular form to be injected into said chamber in central alignment around the outside of the shielding casing of said element, said casing serving to wholly 5 shield said heating element from the gases in said generator.

5. In an oil gas generating apparatus, a sealed oil gas generating chamber, a one-piece electrically heated heating element fixedly hung 10 from one end of said chamber, means spaced away from the lower end of said heating element and positioned at the opposite end of said chamber for injecting an annularly formed mixed spray of oil and steam around the outside of said 15 heating element, and a housing enclosing said heating element and preventing contact between said spray and said heating element, said housing being designed to wholly shield said heating element from the gases in said generating chamber. 20

6. In an oil gas generating apparatus, a sealed oil gas generating chamber, an electrically heated heating element fixedly mounted in an electric conducting housing in said chamber, said heating element and said housing depending from one end of said chamber and being of a length 25 to be substantially co-extensive with the length of said chamber and terminating away from an annular spraying means at the other end of said chamber, said housing being designed to wholly shield said heating element from the gases in 30 said generating chamber.

7. In apparatus for generating oil gas, a sealed oil gas generating chamber, an electrical heating element fixedly hung in an upright position in said chamber and being housed in an electric conducting housing, an oil injecting device 5 spaced away from the lower end of said heating element and positioned in central alignment with said element at the lower end of said chamber for continuously projecting an annularly formed mixed spray of oil and superheated 10 steam into direct contact with the external surface of said housing when said heating element is at a temperature at which steam reacts with hydrocarbon, said shielding casing serving to keep said heating element wholly out of contact with the gases generated by said reaction. 15

8. In apparatus for generating oil gas comprising a sealed internally heated oil gas generating chamber, an electric heating element mounted in said chamber and comprising a casing, an oil injecting device positioned in central alignment with said element at one end of said chamber for continuously projecting an annularly formed mixed spray of oil and superheated steam around the external surface of the casing 25 of said heating element when said heating element is at a temperature at which steam reacts with hydrocarbon, said casing being designed to keep said heating element wholly out of contact with the gases generated by said re- 30 action.

WALTER B. HARRIS.
